PIPING TEMPLATE

Filed Feb. 13, 1946

UNITED STATES PATENT OFFICE

147,026

DESIGN FOR A PIPING TEMPLATE

William H. Skewis, Chicago, Ill., assignor to Crane Co., Chicago, Ill., a corporation of Illinois

Application February 13, 1946, Serial No. 126,538

Term of patent 14 years

(Cl. D52—1)

To all whom it may concern:

Be it known that I, William H. Skewis, a citizen of the United States, residing at Chicago, in the county of Cook and State of Illinois, have invented a new, original, and ornamental Design for a Piping Template, of which the following is a specification, reference being had to the accompanying drawing, forming part thereof.

Fig. 1 is a plan view of a piping template embodying my new design.

Fig. 2 is an edge view thereof.

I claim:

The ornamental design for a piping template, substantially as shown.

WILLIAM H. SKEWIS.
